Primary Examiner — Manpreet Matharu*Assistant Examiner* — Mojtaba Tehrani(74) *Attorney, Agent, or Firm* — Clause Eight IPS; Michael Catania(57) **CLAIM**

The ornamental design for an antenna, as shown and described.

DESCRIPTION

FIG. 1 is a front elevation view of an antenna, showing our new design;

FIG. 2 is a side elevation view thereof;

FIG. 3 is a bottom plan view thereof;

FIG. 4 is a rear elevation view thereof;

FIG. 5 is a top perspective view thereof;

FIG. 6 is a front elevation view thereof, with unclaimed environment not shown;

FIG. 7 is a side elevation view thereof, with unclaimed environment not shown; and,

FIG. 8 is a bottom plan view thereof, with unclaimed environment not shown.

The broken line in the figure drawings represents unclaimed environment only and forms no part of the claimed design.
